A. C. Bartow's Design for "Victor Gas Burner" Stove
Patented April 15, 1962
Ref 15837

UNITED STATES PATENT OFFICE.

A. C. BARSTOW, OF PROVIDENCE, RHODE ISLAND.

DESIGN FOR A GAS-BURNER STOVE.

Specification forming part of Design No. 1,563, dated April 15, 1862.

To all whom it may concern:

Be it known that I, A. C. BARSTOW, of Providence, in the county of Providence and State of Rhode Island, have invented a new and useful Design for Base for Parlor-Stove, entitled the "Victor Gas-Burner;" and I do hereby declare that the following description, taken in connection with the accompanying drawings, to which reference is hereinafter made, is a full and exact specification of the said design.

The figures of the accompanying plate of drawings represent my new design.

Figure 1 is a top or plan view. Fig. 3 is a side view of the same. Fig. 2 is a horizontal section taken in plane of line C D, Fig. 3. Fig. 4 is a transverse vertical section taken in plane of line A B, Fig. 1.

a a in the drawings represent the bottom plate of the base, of the general curved out-

line shown. On the bottom plate *a a* rests a superstructure *c c*, of the ornamental curved form shown, and ornamented on the exterior face with the raised figures *b b* and *e e*, this plate receiving into proper openings in its periphery the draft-door and ash-pit door *r r* and *s s*.

Having thus fully described my new design, what I claim as my invention, and desire to have secured to me by Letters Patent, is—

The new design for base for parlor-stove, entitled the "Victor Gas-Burner," having the general ornamental form and configurations, as hereinabove described, and represented in the drawings.

A. C. BARSTOW.
